UNITED STATES PATENT OFFICE.

MICHAEL MISIC AND EDUARD SCHWEIZER, OF BROOKLYN, NEW YORK.

VALVE-GEAR FOR PUMPING-ENGINES.

SPECIFICATION forming part of Letters Patent No. 409,854, dated August 27, 1889.

Application filed May 1, 1889. Serial No. 309,294. (No model.)

To all whom it may concern:

Be it known that we, MICHAEL MISIC and EDUARD SCHWEIZER, both of Brooklyn, in the county of Kings and State of New York, 5 citizens of the Empires of Austria-Hungary and Germany, respectively, have invented certain new and useful Improvements in Valve-Gears for Duplex Pumping-Engines, of which the following is a specification.

10 This invention relates to an improved valve-gear for duplex pumping-engines, said valve-gear actuating alternately the oscillating slide-valves of the steam-cylinders by which the pumps are operated; and the invention 15 consists of an improved valve-gear for steam-cylinders of duplex pumps, which valve-gear will be fully described hereinafter, and finally pointed out in the claim.

In the accompanying drawings, Figure 1 20 represents a side elevation of a duplex pumping-engine arranged with our improved valve-gear. Fig. 2 is a plan of Fig. 1, and Fig. 3 a vertical longitudinal section through one of the pumps and the corresponding steam-cylinder 25 and steam-chest. Fig. 4 is an end elevation of the steam-cylinders and steam-chest; and Fig. 5, a vertical transverse section of the same on line x x , Fig. 2. Fig. 6 is a detail horizontal section, drawn on a larger scale, of the steam-cylinders and their steam-supply and exhaust-channels. Figs. 7, 8, 9, and 10 are details of 30 the cams for operating the oscillating valve of one steam-engine, and Figs. 11 and 12 are details of the cams for operating the oscillating valve of the other steam-cylinder.

35 Similar letters of reference indicate corresponding parts.

Referring to the drawings, A A are the steam-cylinders, and B B the pump-cylinders, 40 of our improved duplex pumping-engine. Midway between and above the steam-cylinders is supported a cylindrical valve-chest C, which is provided at the interior with two independently-oscillating valves D D, which 45 are supported by an interior circumferential shoulder d , as shown clearly in Fig. 3. The steam-chest is supplied with live steam through a supply-pipe B² and an inverted-T-shaped channel B⁵ in the upper dome-shaped 50 part of the steam-chest C. Each valve D is provided with a spindle D', which pass in op-

posite directions to each other through stuffing-boxes in the opposite heads of the steam-chest to the outside of the same, each spindle being provided with a fixed crank-arm e, 55 which is connected by a pivot-link e' with a crank-arm e², that is securely attached to a longitudinal cam-rod E or E', which turns in suitable bracket-bearings E², attached, respectively, to the steam-cylinders A A and 60 the pump-cylinders B B, as shown in Figs. 1, 2, and 3.

The piston-rods B² of the steam and pump pistons A' B' are guided in stuffing-boxes of the heads of the steam and pump cylinders A 65 and B and provided with upright pillars F, which are firmly clamped to the piston-rods B² and provided at their upper ends with a vertically-adjustable spindle f, that carries an axially-turning disk-shaped head f', which 70 can act on the cams that are attached to the opposite ends of the rocking cam-rods E E', so that the heads f' of the pillars F impart by contact with the said fixed cams on the cam-rods E E' an oscillating motion to the 75 cam-rods E, and by the crank-connection with the oscillating valves oscillating motion to the latter. The play of the pistons of the steam and pump cylinders takes place alternately with that of the adjoining set of steam 80 and pump cylinders, whereby the oscillating slide-valves are correspondingly shifted, so as to produce the required course of live and exhaust steam from the inlet-ports of the steam-chest to the steam-cylinders and from the outlet-ports of the latter to the exhaust-ports of 85 the steam-chest.

Each oscillating valve D is provided with a central circumferential recess d², which forms a channel by which the live steam passes from 90 the channel in the dome-shaped top to the ports of the steam-cylinders. Each valve D is provided in its middle thinner part with a diametrical recess or slot d³, for the shank of an inverted-T-shaped valve D², said valve being large enough to connect the central exhaust-channel m with one of the adjoining steam-channels m' at each side of the same, as shown in Fig. 5, so that simultaneously the inlet of live steam and the outlet of exhaust- 95 steam from each cylinder takes place. The base of the steam-chest C rests on transverse 100

ribs C³, connecting the steam-cylinders, as shown in Fig. 6, the steam-channels leading to opposite ends of the steam-cylinders communicating with said transverse ribs, as shown 5 in Fig. 6. The arrangement of the steam-channels by which the opposite ends of the steam-cylinders are connected with the steam-chest and the oscillating valves of the same are well known and form no part of our 10 invention, and do not require further description.

The spindle of the inner valve D extends through the inner end of the steam-chest C and is connected with the corresponding cam-15 rod E', which cam-rod is provided with fixed cams g, having tapering edges, these cams g being keyed to opposite ends and sides of the cam-rod E', as shown in Fig. 2. The reciprocating motion of the head f' of the corresponding pillar F exerts a direct action on the cams g, and thereby causes their moving in one direction, and also causes the oscillating motion of the cam-rod E' in the same direction, and when moving in the opposite direction the pillar F causes the sideward motion of the cams g in the opposite direction, and thereby the alternate oscillating motion of the inner oscillating valve D. The outer valve D is connected with its cam-rod E at 20 the outer end of the steam-chest and requires different cams than the inner valve D, so as to produce the proper oscillating motion of the said outer valve D. For this purpose the cams h for the outer valve D are hinged in 25 such a manner that the head of the corresponding pillar F, when moving in one direction, first lifts the hinged cam h, so as to pass beyond the same, while by the return motion of the pillar its head f engages the inner inclined edge of the hinged cam h, and produces 30 thereby the sideward motion of the cam and the axially-turning motion of the cam-rod E, so as to impart by the pivoted connection with the valve a corresponding oscillating motion to the latter. When the pillar F arrives at the opposite end of its stroke, it lifts 35 the hinged cam h at the opposite end of the cam-rod E, passes beyond the same, and operates the cam-rod by its next forward motion, so as to produce the corresponding oscillation of the valve. The rear steam-valve D, 40 which is operated from the piston of the right-hand cylinder, (looking from the rear) controls the admission and exhaust of steam in

the left-hand cylinder, and vice versa. The front valve D, which is operated from the piston of the left-hand cylinder, controls the admission and exhaust of steam in the right-hand cylinder, as is shown by the dotted channels in Fig. 6. In this manner the valves 55 D are operated alternately by the engagement of the pillars with fixed and hinged cams on the cam-rods E E', whereby steam is admitted to and exhausted in such a manner that the alternate play of the steam-pistons, 60 and consequently the alternating strokes of the pump-cylinders, are produced.

The cams g g and h h are provided with collars, so that they can be firmly attached to the cam-rods by set-screws passing through 70 said collars, and by which also the proper positions of the cams on the cam-rods are obtained, as shown in Figs. 1 and 2. The cam-rods and crank-connections with the slide-valve produce the regular and uniform functioning of the slide-valves and steam-cylinders and thereby the regular and effective working of the pump.

Having thus described my invention, I claim as new and desire to secure by Letters Patent— 80

The combination, in a duplex pumping-engine, of the steam-cylinders, a steam-chest intermediately between said cylinders, independent oscillating valves in said steam-chest, an interior shoulder between the inner ends 85 of the said valves, spindles secured to the oscillating valves and passing through opposite heads of the steam-chest, cam-rods supported in bracket-bearings, a crank-connection between the spindles of the valves and the cam-rods, fixed cams applied at opposite ends and sides of one cam-rod and hinged cams applied at opposite ends and sides of the other cam-rod, upright pillars attached to the piston-rods of the steam and pump cylinders and 90 provided with heads at their upper ends for engaging said cams and imparting oscillating motion to the slide valves, substantially as set forth.

In testimony that we claim the foregoing as 105 our invention we have signed our names in presence of two subscribing witnesses.

MICHAEL MISIC.
EDUARD SCHWEIZER.
